UNITED STATES PATENT OFFICE.

NELSON F. HOWARD, OF LA FAYETTE, INDIANA.

FENCE-TIGHTENING POST.

Application filed January 19, 1923, Serial No. 613,573. Renewed June 12, 1926.

This invention relates to the type of fence post that is designed for supporting and stretching or tightening wire fencing, especially at a corner or at an end of a line of fencing, the invention having reference more particularly to means for tightening the wire fencing.

An object of the invention is to provide an improved fence-tightening post which shall be of such construction as to be conveniently and easily operated efficiently to tighten wire fencing, and which shall be fire-proof and yet not costly to manufacture and install.

Another object is to provide an improved metallic fence-tightening post that shall be of such construction as to be adapted to be firmly set upon the ground with advantage and economy to avoid excavations for the post.

A further object is to provide an improved metallic fence-tightening post which shall have improved and reliable but inexpensive and powerful fence-tightening means, which may be composed largely of regular stock material and simple castings.

With the above-mentioned and other objects in view, the invention consists in an improved gear-set for tightening and automatically holding wire fencing in stretched condition on posts, and in a novel metallic fence-post supporting the gear-set in a novel and advantageous manner; and further, the invention consists in the novel parts and combinations and arrangements of parts as hereinafter particularly described and claimed.

Referring to the drawings,—Figure 1 is an elevation of the improved post and a single line of wire fencing connected thereto; Fig. 2 is a fragmentary sectional elevation showing details of the post structure on an enlarged scale; Fig. 3 is a top plan of the post; Fig. 4 is a side view of one of the parts of the wire-tightening apparatus on an enlarged scale; Fig. 5 is a perspective view of the frame part of the fence-tightening apparatus; and Fig. 6 is a perspective view of an inexpensive power device comprised in the fence-tightening apparatus.

In the several figures of the drawings similar reference characters indicate corresponding or like parts or features of construction herein referred to in detail.

In the drawings the numeral 1 indicates a portion of the earth or ground on which the

improved post is arranged upon suitable foundation slabs 2 and 3, the latter preferably having a relatively narrow top portion 4.

The frame of the post may be variously constructed and has a base which preferably is composed of metallic side sills 5 and 6 and an end sill 7, the side sills being arranged upon the foundation slabs and extending convergently each to the other from the end sill. A base plate 8 is arranged upon the side sills and secured thereto by means of devices 9, preferably bolts. The base plate has a projection 10 fixed thereon to which an anchor rod 11 is connected that extends at an inclination into the ground in which it is suitably anchored. The base plate is provided centrally with a suitable socket-type journal bearing 12. The frame of the post comprises also two inclined angle-brace portions 13 and 14 that have feet 15 and 16 respectively which are secured upon the end sill 7 by means of suitable devices 17 and 18 respectively, such as bolts. The angle-base portions extend upwardly and convergently each to the other and the upper ends thereof are provided respectively with horizontal arms 19 and 20 that are arranged at a suitable distance above the base plate.

The improved fence-tightening apparatus comprises a frame plate 21 which is arranged upon the arms 19 and 20 and rigidly secured thereto by means of securing devices 22 and 23 extending through the plate and the arm 19, and similar devices 24 and 25 extending through the plate and the opposite arm 20. The plate 21 has bosses 26 and 27 on the top and bottom thereof and also a journal bearing 28 extending through the bosses and so as to be in alinement with the journal bearing 12. The frame plate has also a bearing block 29 fixed on its top which has a journal bearing 30 therein, and the plate has also another bearing block 31 suitably spaced apart from the block 29 and having an inclined slot 32 therein to constitute an open top journal bearing. A power worm 33 is provided which may be cheaply composed of cast iron and is arranged between the bearing blocks and provided with a journal 34 rotatably arranged in the bearing 30, and a journal 35 rotatably arranged in the bearing slot 32. The journals may be portions of a shaft extending through and rigidly secured to the worm,

the journal portion 35 extending out beyond the block 31 and being adapted to have a crank 36 connected thereto. A hollow winding-shaft 37 is rotatably arranged in 5 the journal bearings 12 and 28 and extends upward beyond the frame plate 21 a suitable distance. A supporting pin 38 is secured in the winding-shaft and is supported on the top of the journal bearing 12, and a retaining pin 39 is secured in the winding-shaft beneath the boss 27 on the bottom of the plate 21. A worm gear 40 is arranged on the winding-shaft immediately above the boss 26 on the frame plate and it has an upward extending hub portion 41 in which a securing pin or rivet 42 is arranged that extends through the winding-shaft, the gear being in mesh with the worm 33. The top 10 of the winding-shaft has a suitable cap 43 thereon.

The winding-shaft has a suitable number of transverse holes 44 therein in which horizontal fence wires 45 are secured below the frame plate 21, and as many wires 46 as may 15 be desired above the worm gear 40, in some cases a barbed wire 47 being likewise connected to the upper portion of the winding-shaft. It will be understood that another line of fence may be similarly connected to 20 the winding-shaft when the post is required to be used as a corner post.

In practical use, the post having been properly located and anchored, and the wire fencing connected to the winding-shaft, the 25 crank shaft 36 is connected to the shaft of the worm 33 and operated in the proper direction to wind the fencing wires on the winding-shaft, the rotation of the worm causing the gear 40 to slowly rotate so as to 30 turn the winding-shaft. When the fencing is sufficiently tightened, the crank is removed, the worm preventing backward movement of the gear and the winding-shaft. The tightening operations may be easily and 35 quickly repeated in case the fencing becomes slightly slack.

Having thus described the invention, what is claimed as new is—

1. A fence-tightening post comprising an 40 end sill, two side sills rigidly connected to

the end sill, a base plate rigidly secured to the side sills and having a journal bearing in its top, two inclined angle-brace members secured to the end sill and having horizontal arms respectively on the upper ends 45 thereof positioned separately on one and the same plane materially above the base plate, a top plate rigidly secured upon said arms and having two journal blocks fixed on the top thereof and adjacent to the upper ends 50 of the inclined members, the top plate having also a journal bearing therein, a perforated winding-shaft rotatably supported in said journal bearings and extending higher than the top plate, a gear wheel secured to 55 the winding-shaft upon the top plate, and a power worm arranged between said journal blocks in mesh with the gear wheel and having journal members rotatably supported by the blocks, one of the journal members 60 extending out beyond the top plate to be 65 engaged for rotating the worm.

2. In a fence-tightening post, the combination of an end sill, two side sills integral with the end sill, a base plate secured upon the side sills and having a projection thereon to which an anchor device may be connected, two inclined angle-brace members secured to the end sill and having horizontal arms on the upper ends thereof, a top 70 plate secured upon the tops of said arms and having two journal blocks fixed on the top thereof, one of said blocks being adjacent to one edge of said plate and having an inclined slot bearing in the top thereof, the 75 remaining one of said blocks having a journal bearing therein, a perforated winding-shaft rotatably supported in said base plate and in said top plate and extending higher than the top plate, a gear wheel secured to 80 the winding-shaft upon said top plate, and a power worm arranged between said blocks and having journal members rotatably arranged in the bearings therein, one of said 85 journal members extending out beyond said top plate edge, said worm being in mesh with said gear wheel to rotate the wheel or to prevent rotation of the wheel.

In testimony whereof, I affix my signature.

NELSON F. HOWARD.
